UNITED STATES PATENT OFFICE.

J. McGREGOR ADAMS, OF CHICAGO, ILLINOIS.

DESIGN FOR TORCHES.

SPECIFICATION forming part of Design No. 11,616, dated January 27, 1880.

Application filed December 27, 1879. Term of patent 3½ years.

To all whom it may concern:

Be it known that I, J. McGREGOR ADAMS, of Chicago, in the county of Cook and State of Illinois, have originated a certain new Design for Torches, which is fully described in the following specification, reference being had to the accompanying drawings, making a part thereof, in which—

Figure 1 represents a side elevation of a torch embodying my new design; and Fig. 2, a plan section of the same, taken on the line x x , Fig. 1.

My invention relates to a design for torches intended for use in torchlight-processions, especially of political organizations, and for other similar purposes wherever applicable.

The invention consists in a torch representing in configuration and appearance a ballot-box of the style usually known as the "globe" ballot-box.

In the drawings, A represents the frame of the torch, which is composed of upper and lower rectangular plates a , joined at or near their corners by posts a' , the whole constituting a rectangular skeleton-frame similar to the frame of a globe ballot-box. Within this skeleton-frame the flask or oil-receptacle B of the torch is placed. This flask is in the form of a globe, and may be made of glass or any other

suitable material, and represents the glass-³⁰ globe ballot-depository in a globe ballot-box.

The wick-tube C rises from the upper portion of the globe B, and projects above the upper plate a , and occupies the relative position of the opening in the globe ballot-box ³⁵ through which ballots are introduced into the depository. Thus completed, the torch substantially represents in configuration and external appearance a globe ballot-box.

Upon the sides of the globe-flask may be ⁴⁰ placed inscriptions appropriate to the special use to which the torch is applied. An illustration is shown in Fig. 1 of the drawings; but these inscriptions, ornamental or otherwise, are not an essential feature of the design. ⁴⁵

The torch is mounted in the fork D of the handle by a pivotal connection in the usual way.

Having thus described the characteristic features of my new design for torches, what I ⁵⁰ claim as new, and desire to secure by Letters Patent, is—

The design for torches, as herein shown and described.

J. McGREGOR ADAMS.
